UNITED STATES PATENT OFFICE

2,148,315

ELECTRIC LAMP

Daniel K. Wright, Cleveland Heights, Ohio, assignor to General Electric Company, a corporation of New York

Application March 29, 1938, Serial No. 198,670

8 Claims. (Cl. 176—34)

My invention relates to an electric light projecting device comprising a bulb or envelope at least a portion of which is reflective of light. More particularly, my invention relates to a device of the type disclosed and claimed in my copending applications Serial No. 68,713, filed March 13, 1936, and Serial No. 143,504, filed May 19, 1937, of which the present application is a continuation-in-part. The said device comprises 5 a bulb which is composed of at least two sections of vitreous material united together at their edges by fusion, at least one of said sections being of pressed material and forming a wall which constitutes a comparatively large proportion of the 10 bulb wall. In the preferred form of my invention, both sections are pressed or preformed and united at their edges by fusion. This allows ready access to the inner surfaces of said sections so that they may be properly shaped or coated, and 15 at the same time the union by fusion insures a hermetic seal which will resist gas pressure or a 20 vacuum.

My invention may be embodied in light projecting devices in which the light source is fixed 25 at a definite point, such as the focal point of a reflector or other device for projecting the light. More particularly my invention may be embodied in light projecting devices of the type in which a portion of the enclosure for the light source 30 has a concave light-concentrating surface, preferably paraboloidal, at the focus of which is located the filament or other light source. One of the advantages of such light projectors is that they may be made in small sizes for use as headlamps on vehicles such as automobiles and airplanes where the small sized projector may be effectively incorporated in the stream-lined design of the vehicle. Another advantage is the 35 possibility of extremely accurate location of the light source with respect to the reflecting surface whereby a beam of the correct dimensions and directions may always be secured.

Light projectors have heretofore been proposed in which a bulb was blown with a portion thereof 40 of shaped like a paraboloid, this portion being subsequently silvered on the interior or exterior. However, the silvering of the exterior surface is 45 objectionable because of the reflection of the light by the glass of the bulb. On the other hand it is difficult or impractical in such a case to silver 50 the interior of the paraboloidal portion while maintaining the remainder of the bulb free from silver. Another disadvantage of such a construction lies in the locating of the filament with 55 respect to the reflecting surface since the seal

between the stem on which the filament is mounted and the bulb must be kept plastic while the filament in being located because of inaccessibility to the filament and its supporting wires. If, on the other hand, an attempt is made to silver the 5 paraboloidal portion of the bulb after the filament is mounted, there is a likelihood of depositing some of the silvering material on the filament or of forming a bridge of the material across the leading-in wires and thus short-circuiting 10 the filament. Furthermore, it is very difficult to prevent deposition of the silvering material on the remainder of the bulb in a practical manner.

One of the objects of my invention is to provide a construction for light projectors of the 15 type described in which the above-mentioned disadvantages will be obviated. Another object is to provide a construction which is commercially practicable. One of the features of my invention is the provision of a glass reflector portion, preferably pressed glass, and a separate cover glass or lens portion sealed thereto. The concave glass or parabolic portion may be made with extreme 20 accuracy by pressing, particularly when made of a glass having a low coefficient of expansion, such 25 as that commercially known as Pyrex. By making the bulb or enclosure of separate sections, the reflector section may be conveniently coated internally with a reflecting material before the filament or other light source is mounted therein. 30 The said light source may then be located at the focus of the reflecting portion by optical means as, for example, by placing the unit in a hydrogen or other non-oxidizing atmosphere, energizing the light source, and observing the beam produced thereby on a screen.

While the above-referred-to copending applications disclose the general construction and arrangement of my light projecting device, the present application includes in addition thereto certain specific features of the same, particularly 40 the construction of the sealing surfaces of the reflector and cover glass sections, and the construction of various interengaging means on the said sections for correctly positioning and locking 45 the same in predetermined relationship with respect to each other prior to the sealing together thereof.

Where lamps of the type disclosed in the said copending applications Serial Nos. 68,713 and 50 143,504 are filled with a gas at a pressure above that of the atmosphere, it is necessary that the fused seal between the reflector and cover glass sections be sufficiently strong to resist any tendency of the internal gas pressure to disrupt the 55

same and so separate or pry apart the two sections. To effect such a strong seal it is necessary that the abutting sealing surfaces be completely fused along their entire contact width. However, 5 considerable difficulty has been experienced in producing such a complete seal without impairment of the reflecting coating on the reflector section by the heat attending the sealing operation, and while maintaining the desired optical 10 relationship between the two sections to be sealed together.

Another object of my invention, therefore, is to provide an electric light projection device having an envelope composed of a plurality of optical 15 sections of glass permanently and securely united in definite optical relationship with respect to one another.

Another object of my invention is the provision of suitable sealing surfaces on the glass 20 sections comprising the bulb or envelope of my light projection devices, which surfaces may be readily fused together to provide a complete and strong seal capable of withstanding gas pressures within the envelope greater than that of the 25 atmosphere.

Still another object of my invention is the provision of suitable sealing surfaces on the glass sections comprising the envelope of my projection device which surfaces may be readily fused 30 together to provide a complete and strong seal without impairing the reflector coating on the reflector section and without cracking the glass at and adjacent the seal.

A further object of my invention is to provide 35 positioning means on the reflector and cover glass sections of the projection device for correctly positioning and locking said sections in accurate predetermined optical relationship with respect to each other preparatory to the sealing of the 40 same and for maintaining such predetermined relationship during the sealing together of said sections.

A feature of the invention is the provision of 45 registering surfaces on the lamp sections which are accurately located with respect to the optical surfaces of the envelope sections and are positioned remote from the sealing edges of the sections so that they are unaffected by the softening and distortion thereof during the sealing operations which therefore may be carried to the point 50 where a strong uniform seal will result.

Further objects and advantages of my invention 55 will be apparent from the following detailed description of species thereof and from the accompanying drawings, in which:

Fig. 1 is a horizontal sectional view of a light 60 projection device comprising my invention; Fig. 2 is a front elevation of the projection device shown in Fig. 1; Fig. 3 is an enlarged fragmentary sectional view of the reflector and cover glass sections taken on the line 3—3 of Fig. 2; Fig. 4 is a similar sectional view taken on the line 4—4 of Fig. 2; Fig. 5 is a fragmentary front view of the lower periphery of the reflector section adjacent the vertical center line thereof; Fig. 6 is a fragmentary sectional view of the reflector section taken on the line 6—6 of Fig. 2; Fig. 7 is a fragmentary front elevation of a modification of my invention; Figs. 8, 9 and 10 are enlarged fragmentary sectional views taken on the lines 8—8, 9—9 and 10—10 respectively of Fig. 7; Figs. 11, 12 and 13 are views similar to Figs. 8, 9 and 10 respectively of another modification of my invention; Fig. 14 is a view similar to Fig. 5 of the modified form of reflector section shown in Figs. 76

11, 12 and 13; Figs. 15, 16 and 17 are views similar to Fig. 9 of three further modifications of my invention; Figs. 18 and 19 are views corresponding to Figs. 9 and 10 respectively of still another modification of my invention; Fig. 20 is an enlarged fragmentary sectional view of the modification shown in Figs. 18 and 19 taken on the line 20—20 of Fig. 19; and Figs. 21 and 22, Figs. 23 and 24, Figs. 25 and 26, Figs. 27 and 28, Figs. 29 and 30, and Figs. 31 and 32 are views corresponding to Figs. 9 and 10 respectively of still further modifications of my invention.

Referring to the drawings, particularly Figs. 1 and 2, the light projection device according to my invention comprises a bulb or envelope 10 consisting of a preformed reflector section or member 11 made of pressed glass and a cover glass section or member 12, also made of pressed glass. As is evident from the drawings, the cup or bowl-shaped reflector section 11 is of substantially uniform thickness throughout. The two pressed glass sections 11, 12 are sealed together at their peripheries to form the bulb or envelope 10. The cover glass section may be plain, or it may be a lens having flutes and prisms on the inner surface thereof as shown in Fig. 1, or it may be provided with an inner light diffusing surface such as is produced by facets formed thereon or by frosting the same. It is possible to use such a lens because of the fact that it is made as a separate part from the remainder of the enclosure, whereas with blown glass enclosures or bulbs of the type heretofore produced a suitable lens could not be formed. The reflector and cover glass sections 11 and 12 respectively are preferably made of low-expansion glass, such as that commercially known as "Pyrex" and described and claimed in United States Patent No. 1,304,623, Sullivan et al., issued May 27, 1919. Greater accuracy is obtained with a low expansion glass due to the fact that there is very little contraction of the glass upon cooling. The interior surface 13 of the reflector section 11 may be of paraboloidal or any other suitable shape and is covered with a metallic coating 14 constituting a reflecting surface. By pressing the reflector section rather than blowing the same, the interior surface 13 can be made with extreme accuracy, much more so than is possible with the conventional stamped metal reflectors or with blown glass reflectors, since the plastic glass conforms precisely to the curvature of the accurately formed surface of the plunger of the pressing apparatus. The metallic coating 14 is preferably of aluminum, although any other suitable material may be employed. The said coating 14 is preferably applied to the interior surface 13 by vaporization of the coating metal in a vacuum, as described and claimed in the United States patent application of R. F. Strickland, Serial No. 104,241, filed October 6, 1936.

The reflector section 11 is formed with a pair of openings 15, 15 adjacent the apex thereof, and a central opening 16 at the said apex through which the bulb or envelope 10 is adapted to be exhausted. For conveying current to the device, I have shown a pair of terminal members 17, 17 of the type described and claimed in my United States Patent No. 2,098,080, issued November 2, 1937, although other suitable forms may be employed if desired. The said terminal members 17, 17 consist of cylindrical prongs which may be made of ordinary steel, and have reduced inner end portions 18, 18 extending into the reflector section 11 through the openings 15, 15 therein.

The reflector section 11 is formed with a pair of openings 15, 15 adjacent the apex thereof, and a central opening 16 at the said apex through which the bulb or envelope 10 is adapted to be exhausted. For conveying current to the device, I have shown a pair of terminal members 17, 17 of the type described and claimed in my United States Patent No. 2,098,080, issued November 2, 1937, although other suitable forms may be employed if desired. The said terminal members 17, 17 consist of cylindrical prongs which may be made of ordinary steel, and have reduced inner end portions 18, 18 extending into the reflector section 11 through the openings 15, 15 therein.

Enlarged outer portions 19, 19 of said prongs form shoulders 20, 20 preferably tapered, with the reduced inner end portions 18, 18. Comparatively thin metal cups or thimbles 21, 21 are united, preferably by brazing, to the tapered shoulders 20, 20 of said prongs, and have their edges or rims sealed and embedded in the bosses 22, 22 provided at the outer edges of the openings 15, 15. I prefer to seal the metal cups or thimbles 21, 21 to the glass bosses 22, 22 according to the method disclosed and claimed in the copending United States patent application Serial No. 85,516, filed June 16, 1936, by A. Greiner, E. Westerlund and the applicant herein. The metal cups 21, 21 should be made of a metal to which the fused or softened glass will readily "wet" and stick, and should preferably have the same expansion as the glass, as near as may be. For low-expansion heat-resistant glass of the character hereinbefore indicated, I prefer to make the metal cups 21, 21 of an alloy of iron, nickel and cobalt commercially known as "Fernico" and disclosed and claimed in United States Patent No. 1,942,260, issued January 2, 1934, to H. Scott. I have found that this particular alloy effectively fulfills the above-mentioned requirements or conditions. A filament 23 is mounted on leads 24, 24, which are in turn secured to the inner ends 18, 18 of the terminal members 17, 17. The filament is accurately located at the focus of the paraboloidal reflecting surface by being held in such position in a suitable jig during the attachment of leads 24, 24 to the prong ends 18, 18. The filament 23 is also located in a definite position angularly with respect to the terminal members 17, 17, the said filament and terminal members being preferably positioned in substantially the same plane. After exhaustion of the bulb or enclosure 10 through the opening 16, the same may be filled with an inert gas such as argon, nitrogen, or a mixture thereof. If desired, this gas filling may be under a pressure such as, for example, two atmospheres.

As mentioned above, the cover glass and reflector sections of the light projection device are made separately, being pressed from low-expansion glass, and are then sealed together at their peripheries by means of a pin-point flame from a burner to form the bulb or envelope 10 of the device. To form a strong, permanent and hermetically effective seal between the two bulb sections capable of withstanding considerable internal gas pressures, without impairing the reflecting coating 14 which has been previously applied to the interior surface 13 of the reflector section 11, I have found it highly desirable to construct the sealing surfaces of the reflector and cover glass sections in the particular manner illustrated in the accompanying drawings.

Referring particularly to Figs. 3 and 4, the reflector section 11 is formed at its periphery with a rim 25 having a sealing surface 26 the plane of which is accurately located perpendicularly to the axis of the paraboloidal reflecting surface 14. The cover glass section 12 is likewise formed at its periphery with a sealing surface 27 on a rim 28, the plane of which surface is also accurately located perpendicularly to the axis of said cover glass section. As is evident from the drawings, the sealing surfaces 26 and 27 are spaced outwardly an appreciable distance from the periphery of the interior paraboloidal surface 13 of the reflector section so that the heat necessary to completely fuse the sealing surfaces together along their entire contact area or zone will not

affect or alter the said paraboloidal inner surface 13, or vaporize or otherwise impair the reflecting coating 14 on said surface. Furthermore, the sealing surfaces 26 and 27 are made of relatively small width or radial extent, such as, for instance, one-eighth inch or thereabouts, so that the heat necessary to completely fuse said surfaces together can be localized and the seal thus formed completely in a very short time, before sufficient heat is conducted by the adjacent glass 10 to the inner paraboloidal surface 13 of the reflector section 11 to adversely affect the same or the reflecting coating 14 thereon. To prevent cracking of the glass, among other things, at and adjacent the seal, the abutting sealing surfaces 15 26 and 27 are made substantially flat and uninterrupted throughout their entire extent, as shown in the drawings. By completely fusing the abutting sealing surfaces from their outer peripheries clear through to their inner peripheries, a feature made possible by the particular construction of the sealing surfaces described above, the existence of sharp crevices leading to the inner edge of the fused joint is entirely avoided, thereby eliminating the possibility of 25 the internal gas pressure separating or prying apart the two sections 11 and 12 comprising the bulb or envelope 10, a result which would normally occur, if such crevices were actually present, from the wedging action exerted on the 30 walls of such crevices by the internal gas pressure.

To further insure against the possibility of separation of the two sections 11 and 12 by the internal gas pressure, both the reflector and the 35 cover glass sections 11 and 12 are provided with annular grooves 29 and 30, respectively, immediately adjacent the inner peripheries of the sealing surfaces 26 and 27 on said sections. The grooves 29 and 30 are substantially semi-circular 40 in cross section and are adapted to lie opposite one another when the cover glass and reflector sections are sealed together in correct optical relationship with respect to each other so that the outer edges of said grooves are exactly 45 aligned, as shown in Figs. 3 and 4. The result is that the surfaces 31, 32 of the reflector and cover glass sections immediately contiguous to the inner periphery of the sealing surfaces 26 and 27 approach the latter at approximately 50 right angles. When proper care is used in the sealing operation, the said inner surfaces 31, 32 of the two envelope sections form a continuous and uninterrupted wall extending substantially perpendicularly to the plane of the sealing surfaces. The envelope surfaces immediately adjacent the inner edge of the fused joint therefore have practically no convergence at the point of fusion. This is of particular importance where the envelope is to be filled with a gas under pressure since it eliminates all tendency for localization of tensile stresses in the seal which might cause its failure.

While the reflector and cover glass sections 11 and 12 can be pressed so as to have remarkably 65 true optical surfaces, it has been found quite difficult to maintain accurate alignment of these surfaces while their sealing edges 26, 27 are softened and joined together. This is particularly true when the sections are relatively thick 70 and the heat required to completely fuse the sealing surfaces 26, 27 together is considerable. In the present construction, definite optical alignment of the reflector and cover glass sections 11 and 12 is maintained at all times by 75

the provision thereon of a reference zone comprising positioning and interlocking means which are independent of the sealing surfaces 26, 27 and are relatively unaffected by the heating and softening of the rims 26 and 28 of said sections during the sealing operation. The said registering and positioning means comprises a recessed annular reference surface or seat 33 on the cover glass disposed in a plane normal to the axis thereof. The said recessed seat 33 is spaced slightly inward from the annular groove 30 so as to form an annular lip or ridge 34 between said groove and seat. The inner surface 35 of the ridge 34 is made substantially straight and is tapered at a definite angle, preferably 30°, with respect to the axis of the cover glass. Inwardly of and immediately adjacent the groove 29 therein, the reflector section is formed with an upstanding annular embossment 36 adapted to lie opposite the annular reference seat 33 on the cover glass section when the two sections are properly aligned with one another. The embossment 36 preferably extends outwardly beyond the plane of the sealing surface 26 on the reflector section so as to project into the recess formed by the recessed reference seat 33 on the cover glass section and overlap the annular ridge 32 thereon. As shown in Fig. 3, however, the embossment 36 is spaced a slight distance from the annular ridge 34 on the cover glass section and from the annular reference seat 33 so as to provide a passageway 37 therebetween communicating with the annular chamber formed by the grooves 29, 30 in the reflector and cover glass sections. The annular embossment 36 is formed with a plurality of projections 38 extending upwardly from the upper and outer surfaces of said embossment and spaced uniformly around the circumference thereof, said projections being adapted to abut against and snugly fit the recessed reference seat 33 and the tapered inner surface 35 of the ridge 34 to thereby accurately align the two envelope sections. In order to properly engage the reference seat 33 and the tapered surface 35 respectively, the upper surfaces 39 of the projections 38 are so formed as to lie in a common plane normal to the axis of the paraboloidal reflector section 11 while the outer surfaces 40 of said projections are tapered at the same angle as that of the said tapered surface 35. The projections 38, together with the reference seat 33 and tapered surface 35, thus provide means for positioning and maintaining the reflector and cover glass sections in correct optical relationship with respect to each other transversely or radially of the reflector axis.

To position and maintain the reflector and cover glass sections in correct rotative or angular relationship with respect to each other, I have provided additional interlocking positioning means comprising a small conical recess 41 (Fig. 4) in the sealing surface 26 on the reflector section, and a corresponding conical locking lug 42 projecting from the sealing surface 27 on the cover section. The conical recess 41 is adapted to snugly receive the locking lug 42 to thereby lock the two envelope sections in accurate angular relation preparatory to the sealing together of the same.

Thus, where the cover glass section 12 is in the form of a lens having prisms and flutes thereon, as shown in Figs. 1 and 2, the lug 42 may be so located on such lens with respect to the said flutes and prisms as to properly position the same with respect to the reflector section 11 and the

filament 23 mounted therein. To correctly mount the projection device in its supporting holder, the outer surface of the reflector section 11 may be provided with a positioning lug 43 (Figs. 1 and 4) adjacent the periphery of said section and preferably in angular alignment with the conical recess 41 in the sealing surface 26.

In assembly of the lamp or projection device, the reflector section 11, which has been previously provided with the filament 23, terminal members 17 and reflecting coating 14, is placed in a sealing chuck and a cover glass section placed thereon with the conical lug 42 engaging in the conical recess 41 and the various projections 38 each engaging the reference seat 33 and tapered surface 35. When so positioned, the sealing surfaces 26, 27 are preferably slightly separated from each other, but after proper heating the said surfaces soften and are fused together, the cover glass being supported throughout this process on the projections 38. Thus the predetermined relation of the cover glass to the reflector section is maintained undisturbed despite the heating and fusing together of the rims of the two sections.

During the sealing operation the depending lip 25 or ridge 34 on the cover glass, together with the upstanding embossment 36 on the reflector section, act as baffles across the line or plane of the seal and prevent such hot gases as are forced into the envelope by the sealing flames from impinging directly on the reflecting coating 14 or the various flutes and prisms on the cover glass. Since the embossment 36 is spaced from ridge 34 to provide the passageways 37 communicating with the chamber formed by the grooves 29 and 30, any 35 chance of undesired gases being trapped in said chamber during exhaustion of the envelope is completely eliminated.

Referring now to the modification shown in Figs. 7 to 10 inclusive, the projection device there shown differs from the previous form in that the reference seat and the reference projections are reversed, the reference seat being located on the reflector section 11 while the reference projections are located on the cover section 12. Thus 45 as shown in Figs. 8, 9, and 10, the reflector section 11 is formed with an annular reference surface 44 extending around the margin of the parabolic surface 13 in a plane normal to the axis thereof. This surface 44 is bounded by an annular ridge 45 of glass the inner edge 46 of which is equidistant from the axis of the parabolic surface 13. The cover glass section 12 is formed with a depending annular embossment 47 so located thereon as to lie directly opposite the reference surface 44 on the reflector section when the two sections are correctly aligned. A number of uniformly spaced projections or buttons 48 extend from the said embossment 47. While most of these projections are shaped as to fit snugly within ridge 60 45 and bear against reference surface 44, one projection is enlarged into a circular boss 49 which bears against surface 44 and registers with a semi-circular notch 50 formed in the ridge 45. As in the previous form of the invention, the 65 embossment 47 acts as a baffle across the line of the seal during the sealing operation, preventing any hot gases that may be forced into the envelope by the sealing flames from impinging directly on the reflecting coating 14 or on the cover glass prisms and thereby impairing the same. Inasmuch as the embossment 47 is spaced from surface 44 by the thickness of the buttons or projections 48, any chance of undesired gases being trapped in the annular chamber between the 75

embossment and the sealing rims is completely eliminated.

The modification illustrated in Figs. 11 to 14 inclusive is very much the same as the form of the invention shown in Figs. 1 to 6, the angular positioning means however being slightly different. Thus in the modification the angular positioning means consists of a circular boss 51, similar to the boss 49 in Fig. 7, which is adapted to fit snugly in a semi-circular notch 52 in the ridge 53 on the cover glass. The upper surface 39' of said boss 51 is adapted to engage the reference seat 33 in the same manner as the upper surfaces 39 of the projections 38. The semi-circular grooves 54 and 55 in the reflector and cover glass sections respectively are made slightly smaller than the grooves 29, 30 shown in Figs. 3 and 4.

The modification shown in Fig. 15 differs from the construction shown in Figs. 11 to 14 merely in the shape of the annular grooves 56 and 57 in the reflector and cover glass sections respectively, the said grooves being relatively shallow and of extended width.

In Fig. 16 the groove 58 in the reflector section 11 is continued inwardly to the inner surface 13 thereof to thereby provide, in effect, an annular ledge or recess from which a plurality of reference buttons or projections 59 extend. The cover glass 12 is formed with an annular groove 60 adapted to lie opposite groove 58 and is also formed with a depending embossment 61 having an annular ridge 62 and reference surface 63. The said ridge 62 and surface 63 provide a seat, similar to that provided by the ridge 34 and surface 33 in Figs. 3 and 4, for the various projections 59 on the reflector section. The ridge 62, since it extends across the line of the seal, further acts as a baffle during the sealing operation, the same as ridge 34 in Figs. 3 and 4 and embossment 47 in Figs. 8 to 10. The angular positioning means between the reflector and cover glass sections in the modification shown in Fig. 16 may either be of the form illustrated in Figs. 1 to 6 or of the form illustrated in Figs. 11 to 14.

In the modification shown in Fig. 17 the annular groove 64 in the reflector section 11 provides a reference surface 65 for cooperation with a plurality of uniformly spaced projections 66 on the depending embossment 67 of the cover glass section 12. The groove 64 is bounded at its inner extremity by an annular ridge 68, the outer surface 69 of which is tapered so as to provide a seat for the tapered inner surface 70 of the projections 66. As in the previous forms of the invention, the cover glass 12 is provided with an annular groove 71 adapted to lie opposite the groove in the reflector section 11. The angular positioning means (not shown) in this modification may be of either of the forms previously described in connection with Figs. 1 to 10.

Referring to the modification shown in Figs. 18 to 20, the groove 72 in the cover glass 12 is continued inwardly to the inner wall 73 thereof to form an annular ledge providing a reference surface 74 against which an annular upstanding embossment 75 on the reflector section 11 is adapted to bear. The said embossment forms the inner boundary of the groove 76 in the reflector section, and is recessed at uniformly spaced points around its circumference, preferably 90° apart, to thereby provide notches 77 having tapered side walls 78, 79 and a lower wall 79 coinciding with the bottom of the groove 76. The cover glass 12 is formed with a corresponding number 75 of depending projections or lugs 80 adapted to

extend into the notches 77 and so lock the reflector and cover glass sections 11 and 12 respectively in correct relationship with one another. The side walls 81, 81 of the projections 80 are tapered so as to seat on the tapered walls 78, 78 of the notches 77. Also, the height of the projections 80 is made less than the depth of the notches 77 so that the bottom wall 82 of said projections is slightly spaced from the bottom wall 79 of the notches, thereby providing a passageway 10 communicating with the annular chamber formed by the oppositely disposed grooves 72 and 76 through which passageway any gases trapped in said chamber may be withdrawn.

In the modification shown in Figs. 21 and 22, 15 the reflector section 11 is formed immediately adjacent the inner edge of the sealing surface 26 with an annular groove 83 of relatively small semi-circular section. Inwardly of said groove the reflector section is provided with an upstanding embossment 84 the upper surface 85 of which constitutes a reference surface. The cover glass 12, inwardly of the sealing surface 27 thereon, is recessed to form a ledge 86 from which a plurality of uniformly spaced projections 87 depend, said 20 projections being adapted to engage the reference surface 85 to thereby properly align the reflector and cover glass sections 11 and 12 respectively. To further assist in aligning the said sections the side wall 88 formed by the recess or 25 ledge 86 is tapered to provide a seat for a plurality of similarly tapered projections 89 extending from the outer surface 90 of the embossment 84. As shown in Fig. 22, the angular positioning means in this modification comprises a lug 91, preferably 30 a semi-circular boss, extending from the tapered side wall 88 and adapted to snugly fit into a correspondingly shaped recess 92 in the outer surface of the embossment 84. To permit evacuation 35 of the annular chamber formed by the groove 83, the outer surface 90 of the embossment 84 is spaced a slight distance from the tapered side wall 88 to thereby provide a passageway communicating with said chamber.

Referring to the modification illustrated in 45 Figs. 23 and 24, both the reflector and cover glass sections 11 and 12 are formed with annular grooves 93 and 94 respectively substantially semi-circular in cross-section and adapted to lie opposite one another when the said sections are 50 properly aligned. The outer surface 95, however, of the groove 93 is made flat and is tapered outwardly to form a reference seat for an annular ridge 96 formed on the cover glass immediately adjacent the sealing surface 27 thereon. The 55 outer wall 97 of the ridge 96 is tapered to correspond to and seat against the tapered outer surface 95 of the groove 93. Thus, the engaging surfaces 95, 97 form continuations of the sealing surfaces 26, 27 on the reflector and cover 60 glass sections 11 and 12 respectively and assist in properly aligning said sections. Inwardly of the groove 93 therein, the reflector section 11 is provided with an upstanding embossment 98 the upper surface 99 of which forms a reference surface 65 against which a plurality of depending projections 100 on the cover glass are adapted to bear. As shown in Fig. 24, one of these projections is extended to provide a locking lug 101 which is adapted to project into a corresponding recess 102 in the embossment 98 to thereby 70 constitute angular positioning means for the reflector and cover glass sections.

The modification shown in Figs. 25 and 26 is substantially the same as the construction dis- 75

closed in Figs. 21 and 22 except for the cross-sectional shape of the grooves 103 and 104 in the reflector and cover glass sections respectively. Thus in Figs. 25 and 26, the groove 103 in the reflector section 11 is made relatively shallow and is of extended width, while the groove 104 in the cover glass section is formed with an outwardly tapering outer wall 105.

In the modification disclosed in Figs. 27 and 10 28, the cover glass 12, inwardly of the sealing surface 27 thereon, is recessed to form an angular ledge 106 from which a plurality of uniformly spaced reference projections 107 depend, said projections being adapted to bear 15 against a reference surface 108 constituting the upper surface of an upstanding embossment 109 formed on the reflector section 11. To further aid in aligning the reflector and cover glass sections the side wall 110 formed by the recess or 20 ledge 106 is tapered so as to uniformly seat on the tapered outer wall 111 of the upstanding embossment 109. The engaging surfaces 110 and 111 thus form continuations of the sealing surfaces 26, 27 on the reflector and cover glass 25 sections respectively as well as providing means for properly aligning the said sections transversely of each other. As shown in Fig. 28, one of the projections on the cover glass is extended to provide a locking lug 112 which is adapted to 30 snugly fit into a suitably shaped recess 113 in the embossment 109 to thereby form angular positioning means for the reflector and cover glass sections.

In Figs. 29 and 30, the sealing surfaces of the 35 reflector and cover sections are slightly curved instead of being straight or flat as in the previous forms of the invention. Referring to Figs. 29 and 30, the front surface of the reflector section rim 25 is recessed at its inner periphery to 40 form an annular ledge 114 providing a reference surface against which a plurality of projections 115 on a depending embossment 116 on the cover section are adapted to bear. The upper surface of the annular ridge 117 formed at the outer 45 periphery of the rim 25 by the recessing thereof, is curved about a center located approximately on the edge 118 of the said rim to thereby provide an arcuate sealing surface 119. The cover glass 12 is formed with an annular depending 50 embossment 120 inwardly of the edge 121 thereof, the outer surface 122 of which embossment is curved to correspond with the curvature of the sealing surface 119 on the reflector section 11. Intermediate the annular embossments 116 and 55 120 on the cover glass section, the latter is formed with an annular groove 123. As in the previous modifications illustrated in Figs. 23 to 28, one of the projections on the cover section 12 is extended to provide a locking lug 124 (Fig. 30) 60 which is adapted to snugly fit into a recess 125 in the ledge 114 to thereby provide angular positioning means for the reflector and cover sections.

In the modification shown in Figs. 31 and 32, 65 the sealing surfaces on the reflector and cover sections extend throughout their entire width at an angle to the plane normal to the reflector axis instead of parallel thereto, as in most of the previous modifications. Other than this 70 change the construction is very much the same as that shown in Figs. 29 and 30. Referring to Figs. 31 and 32, the inner surface 126 of the annular ridge 117 on the reflector section rim 25 is inclined at an angle of approximately 60° 75 or thereabouts to the plane of the reference sur-

face 114 and forms the sealing surface on said section. The edge 127 of the rim 28 on the cover section is correspondingly inclined to uniformly seat on the sealing surface 126 and thus form the sealing surface on the cover section 12. As 5 a consequence of the inclination of the sealing surfaces 126, 127, the said surfaces constitute supplementary aligning means, in addition to the projections 115 and reference surface 114, for properly aligning the reflector and cover glass 10 sections.

What I claim as new and desire to secure by Letters Patent of the United States is:

1. An electric projection lamp comprising a light source, an enclosure comprising a glass reflector portion and a glass cover portion assembled and in contact with each other at their rims, said contacting rims comprising a sealing zone in which the rims are united by fusion and a registering zone in which the said rims seat together 20 but are not united.

2. An electric projection lamp comprising a light source, an enclosure comprising a glass reflector portion and a glass cover portion assembled and in contact with each other at their rims, 25 said contacting rims comprising a sealing zone in which the rims are united by fusion and a registering zone in which the said rims seat together but are not united, said sealing zone being spaced from said registering zone.

3. An electric lamp enclosure comprising a glass reflector section and a cover glass section each having optical surfaces designed to coat to produce a definite light distribution, registering means on said sections determining their optical relationship in assembled position, said registering means comprising a reference surface on said cover glass section and a plurality of reference projections on said reflector section positioned in registry with said reference surface, 40 and sealing means forming a gas-tight joint between said sections, said registering means being wholly independent of said sealing means.

4. An electric lamp enclosure comprising a glass reflector section and a cover glass section each having optical surfaces designed to coat to produce a definite light distribution, registering means on said section determining their optical relationship in assembled position, said registering means comprising a reference surface on 45 said reflector section and a plurality of reference projections on said cover glass section positioned in registry with said reference surface, and sealing means forming a gas-tight joint between said sections, said registering means being wholly 50 independent of said sealing means.

5. An electric lamp enclosure comprising a glass reflector section and a cover glass section provided with cooperating annular rim portions, each of said sections having optical surfaces designed to coat to produce a definite light distribution, said rim portions being formed at their outer peripheries with oppositely disposed annular sealing surfaces and at their inner peripheries with registering means determining the optical relationship of said sections in assembled position and having opposed annular grooves intermediate the said sealing surfaces and registering means.

6. A glass enclosure for a light projection device comprising a reflector section having a reflecting surface, a reference surface adjacent its periphery and disposed in a plane normal to the axis of said reflecting surface, and a sealing surface at its periphery and spaced from said 70 75

reference surface, and a cover section for said reflector section, said cover section having an annular reference embossment adjacent its periphery and engaging said reference surface to thereby position said sections in correct predetermined relationship with one another, and a sealing surface on said cover section at the periphery thereof and disposed in corresponding relation to the sealing surface on said reflector section, said sealing surface being spaced from said reference embossment.

7. A glass enclosure for a light projection device comprising a reflector section and a cover section, said cover section having a reference surface adjacent its periphery and a sealing surface at its periphery, said sealing surface being spaced from said reference surface, said reflector section having an annular reference embossment adjacent its periphery and engaging said reference surface to thereby position said sections in correct predetermined relationship with one another, and a sealing surface on said re-

flector section at the periphery thereof and disposed in corresponding relation to the sealing surface on said cover section, said sealing surface being spaced from said reference embossment.

8. A glass enclosure for a light projecting device comprising a reflector section provided with a reflecting coating on its inner surface, said reflector section having a sealing rim at its periphery provided with a substantially flat sealing surface, a cover section for said reflector section having a sealing rim at its periphery provided with a similarly flat sealing surface disposed in corresponding relation to the sealing surface on said reflector section, and an annular embossment on one of said sections disposed between said reflecting coating and said cooperating sealing surfaces and intersecting the plane of said sealing surfaces to thereby form a baffle serving to protect the said reflecting coating from the sealing flames.
